B. J. Craig,
ATTORNEY.

UNITED STATES PATENT OFFICE

MAX E. ZIMMERMANN, OF LOS ANGELES, CALIFORNIA, ASSIGNOR OF ONE-HALF TO
KARL SCHUMACHER, OF LOS ANGELES, CALIFORNIA

COVER GRIPPING DEVICE

Application filed January 14, 1931. Serial No. 508,696.

This invention relates to improvements in cribs and children's beds.

The general object of the invention is to provide an improved crib which includes a 5 novel cover gripping means.

Another object of the invention is to provide a crib including a combination closure for the side and cover gripping means.

An additional object of my invention is to 10 provide a novel shiftable side for a crib.

Other objects and advantages of this invention will be apparent from the following description taken in connection with the accompanying drawings wherein:

15 Fig. 1 is a side elevation of a crib embodying the features of my invention.

Fig. 2 is a section taken on line 2—2 of Fig. 1.

20 Fig. 3 is a view similar to Fig. 2 showing the closure member in an open position.

Fig. 4 is an enlarged fragmentary section showing covers being held in position by the cover gripping means.

25 Fig. 5 is an enlarged fragmentary side view partly in section showing the structural details of the hinge and latching mechanism for the closure member.

Fig. 6 is an enlarged fragmentary top plan view of the crib.

30 Fig. 7 is a side elevation of a crib embodying a modification of my invention.

Fig. 8 is a section taken on line 8—8 of Fig. 7 with the crib guard.

35 Fig. 9 is an enlarged fragmentary section taken on line 9—9 of Fig. 7.

Fig. 10 is a side elevation of a crib embodying another modification of my invention.

Fig. 11 is a cross section through the crib shown in Fig. 10.

40 Fig. 12 is an enlarged fragmentary top plan view showing one of the latch devices.

Fig. 13 is a section taken on line 13—13 of Fig. 12, and

45 Fig. 14 is a fragmentary elevation of a catch member.

Referring to the drawings by reference characters I have indicated a crib embodying the features of my invention generally at 10.

50 As shown this crib includes corner posts 11 which are connected longitudinally by a

front rail 12 and a rear rail 13 and transversely by lower end bars 14 and upper end bars 15. Spaced above the rear rail 13 a bar 16 is provided and in the space between the rail 13 and bar 12 and between the end bars 14 and 15 a plurality of spaced slats 17 are provided.

The rails 12 and 13 are adapted to support a bedspring 18 which may be of any desired type and on which a mattress 19 is adapted to be positioned. Spaced above the front rail 12 and secured to the front posts 11 I provide a bar 20 and secured to the rail 12 and the bar 20 I provide a panel 21 which includes a portion 22 extending above the bar 20.

For closing the front of the crib I provide a gate which is indicated generally at 23 and includes a bottom rail 24 and a top rail 25 which are connected adjacent their ends by end bars 26 and between the bottom rail 24 and the top rail 25 I provide a plurality of spaced slats 27.

The gate 23 is pivotally connected to the corner posts 11 by crank shaped hinge members 28 shown in detail in Fig. 4. One arm 29 of the crank member 28 is positioned in a bushed aperture 30 in the end bar 26 and the other arm 31 extends through an elongated aperture 32 in a plate 33 on the corner post 11 and is positioned in a similar elongated aperture 34 in the corner post.

Positioned in a recess 35 in the corner post and engaging the arm 31 of the crank member 28 I provide a coiled spring 36 which exerts a downward pressure on the arm 31.

For closing the recess 35 I provide a cover plate 37 which is secured to the corner post by screws 38. For assuring correct operation of the hinge device I provide a plate 39 which is secured to the end bars 26 of the gate by screws 40 and is positioned adjacent the shank 41 of the crank member 28.

For retaining the gate 23 in a closed position I provide a latch mechanism 42 preferably on each of the front corner posts 11. As shown each of the latches includes a spring pressed plunger 43 having a beveled end 44 and an operating knob 45. When the gate 23 is in a closed position the plunger

ers 43 of the latch mechanism 42 engage plates 46 which are secured to each of the end bars 26 and retain the gate in a closed position, the beveled ends 44 of the plungers 5 allowing the plates 46 to retract the plungers and move past the same.

When the gate 23 is in a closed position as shown in Figs. 1, 2 and 4, the lower rail 24 thereof is positioned adjacent the top surface of the bar 20 and adjacent the inner surface of the upwardly extending portion 22 of the panel 21.

When one desires to place a child in the crib 10 he releases the latches 42 and swings the top of the gate 23 outward and downward to the position shown in Fig. 3. The length of the shank 41 of the hinge members 28 allows the gate to assume a straight vertical position on the outside of the panel 21 as may be clearly seen in Fig. 3.

The operator then places the child in the crib and covers it with the desired covers and places the edges of part or all of the covers which are indicated at 48 in Fig. 4, 25 over the bar 20 and the panel 21. After so doing the operator grasps the top rail 25 of the gate and swings it upward. As the gate is swung upward it first pivots about the axis of the arms 29 of the hinge members 28 and then the plates 39 engage the shanks 41 of the hinge members and thereafter the gate swings about the axis of the arms 31. As the gate approaches its closed position the lower rail 24 thereof engages the covers 48 and 30 moves them into engagement with the upper surface of the upwardly extending portion 22 of the panel 21.

When the gate is in a closed position and latched the covers 48 are tightly clamped 40 between the inner surface of the panel 21 and the outer surface of the gate rail 24 and between the upper surface of the bar 20 and the lower surface of the rail 24 as clearly shown in Fig. 4.

45 The springs 36 which engage the arms 31 of the hinge members 28 allow the gate to move upwardly to compensate for the thickness of the covers which are positioned between the rail 24 and the bar 20 and the 50 spring or natural resiliency of the material of which the gate is made compensates for the thickness of the covers which are positioned between the rail 24 and the panel 21. The latch plates 46 are made sufficiently long 55 to compensate for the greatest amount of vertical movement of the hinge arms 31.

In Figs. 7, 8 and 9 I have indicated generally at 50 a crib embodying a modification of my invention. As shown this crib 60 includes corner posts 51 which are connected longitudinally by a front rail 52 and a rear rail 53 and transversely by lower end bars 54 and upper end bars 55. Spaced above the rear rail 53 a bar 56 is provided and in the space between the rail 53 and the bar 56 and

the end bars 54 and 55 slats 57 are provided.

The rails 52 and 53 are adapted to support a bed spring 58 of any desired type on which a mattress 59 is adapted to be positioned. Spaced above the front rail 52 and secured to the front corner posts 51 I provide a bar 60 having a groove 61 preferably of V shape in its upper face. Positioned between the rail 52 and the bar 60 I provide a panel 62.

70 For closing the front of the crib 50 I provide a gate 63 which includes a bottom rail 64 and a top rail 65 which are connected adjacent their ends by end bars 66 and between the bottom rail 64 and the top rail 65 I provide a plurality of spaced slats 67. The under surface of the bottom rail 64 of the gate is V shaped to correspond to the V shaped groove 61 in the bar 60 and is adapted to fit therein as clearly shown in Fig. 9.

75 Pivotedly mounted as at 69 on each end of the upper rail 65 of the gate I provide a block 70 having an aperture 71 therein in which a rod 72 is positioned. The upper end of the rod 72 is secured to the inner side of the corner post 11 by a member 73 and extends straight downward to a point below the lower end of the block 70 when the gate is in a closed position and then it is curved outwardly as at 70' to a point spaced beyond the outer face 80 of the corner post whence it extends straight downward as at 70'' a distance and is bent back and at an angle and is secured to the corner post as indicated at 74 by screws or other suitable securing means.

85 For retaining the gate 63 in a closed position I provide a spring pressed latch device 75 on each of the blocks 70. The plungers 76 of the latches are adapted to engage teeth 77 on plates 78 which are secured to the inner sides of the adjacent corner posts and are adapted to prevent upward movement of the gate.

90 To open the gate 63 the operator releases the latches 75, moves the gate upward until the lower edge of the rail 64 thereof clears the top of the bar 60 and then swings the lower end of the gate outward and lowers it. As the rods 72 are curved outward and the lower portion thereof is spaced beyond the front of the corner post the gate, when in a lowered 95 position, will be suspended vertically in front of the crib.

100 To close the gate 63 the operator raises the gate until the lower end of the rail 64 is above the bar 60 and then lowers the gate so that the lower V-shaped face of the rail 64 is positioned in the V-shaped groove 61 of the bar 60.

105 When it is desired to secure bed covers in position in the crib 50 the gate 63 is raised and the ends of the covers positioned over the bar 60 and then the gate is moved downward. When the gate is moved downward the lower surface of the rail 64 engages the covers and forces them into the groove 61 thereby 110 clamping them in position between the sur-

face of the V-shaped groove and the surface of V-shaped portion of the gate rail 64.

In Figs. 10 and 11 I have indicated a crib embodying a further modification of my invention generally at 80. As shown this crib includes corner posts 81 which are connected longitudinally by a front rail 82 and a rear rail 83 and transversely by lower end bars 84 and upper end bars 85. Spaced above the rear rail 83 a bar 86 is provided and in the space between the rail 83 and the bar 86 and between the end bars 84 and 85 a plurality of spaced slats 87 are provided.

The rails 82 and 83 are adapted to support a bed spring 88 which may be of any desired type and on which a mattress 89 is adapted to be positioned. Spaced above the front rail 82 and secured to the front corner posts 81 I provide a bar 90 and secured to the rail 82 and the bar 90 I provide a panel 91 which includes a portion 92 extending above the bar 90.

For closing the front of the crib 80 I provide a gate which is indicated generally at 93 and includes a bottom rail 94 and a top rail 95 which are connected adjacent their ends by end bars 96 and between which I provide a plurality of spaced slats 97. Adjacent each end of the gate 93 I provide a rod 98 one end of which is secured to the lower rail 94 and the opposite end to the top rail 95.

Extending longitudinally along the front of the crib adjacent the upper end of the panel 91 I provide a rod 99 which is secured to the front corner posts as at 100 by screws or other suitable securing means.

Pivots mounted on the rod 99 adjacent each of the gate rods 98 I provide bearing blocks 101 each of which is provided with an aperture 102 in which the adjacent gate rod 98 is positioned and in which it is freely slideable.

For retaining the gate 93 in a closed position I provide a spring pressed latch device 103 adjacent each end of the rail 95 and on the front corner posts I provide plates 105. Each of the latches include a plunger 104 having a beveled end 106 and a beveled side 107 and the inner face of the plates 105 are provided with ratchet teeth 108.

When the gate 93 is in a closed position the plungers 104 of the latches are positioned in the rear of the plates 105 thus preventing the gate from being moved outward and the beveled side 107 of the plungers engage one of the teeth 108 of the adjacent side plate and prevents upward movement of the gate.

To open the gate 93 the latches 103 are released and the top rail 95 is swung outward and downward about the axis of the rod 99 and then the gate is lowered until the bearing blocks 101 engage the bottom rail 94.

To close the gate 93 the operator grasps the top rail 95 and swings it upward and inward about the axis of the rod 99 and then lowers

it so that the lower rail 94 rests on the bar 90.

When it is desired to secure the bed covers in position in the crib 80 the latches 103 are released, the gate 93 raised and the edges of the covers positioned over the bar 90 and the upper edge of the panel 91. The gate is then lowered and as it is so moved the lower face of the gate rail 94 engages the covers and moves them down against the bar 90. Thus the covers are clamped between the gate rail 94 and the bar 90 and between the rail 94 and the upwardly extending portion 92 of the panel 91.

Although in the following claims I refer to a crib, it will be understood that my invention may be used in connection with beds, cots, sofas, and all articles of furniture intended to recline and sleep or rest on without departing from the spirit of the invention.

It will also be understood that I may, if desired, reverse my cover holding arrangement by putting the cover engaging bars on the covers, all within the scope of the appended claims.

From the foregoing description it will be apparent that I have provided a crib or bed which is highly efficient for the intended purpose and which can be economically manufactured.

Having thus described my invention, I claim:

1. In combination with a crib including end portions and side portions, one of said side portions including a panel, a closure gate adjacent to said panel, and pivot means arranged above said panel and connecting said end portions and said gate to mount said closure gate for swinging movement with the lower part thereof moveable outwardly against said panel to thereby hold bed covers against said panel.

2. In combination with a crib, including end portions and a back portion, each of said end portions including a vertical rear corner post and a front corner post, a horizontal member connecting said front corner posts, a second member associated with said horizontal member and arranged adjacent thereto and above the bottom of said horizontal member to form a closure receiving portion, a closure gate for the front of said crib, said closure gate including end bars connected by upper and lower rails, said lower rail when said gate is in a closed position being positioned in said closure receiving portion, and hinge means connecting said closure gate to said front corner posts permitting said gate to swing outwardly through a semicircle whereby the gate is disposed outside of and adjacent said second member with the top rail substantially below and the bottom rail above said second member.

3. In combination with a crib including end portions and a back portion, each of said end portions including a vertical rear corner

post and a front corner post, a horizontal rail connecting said rear corner posts and a horizontal front rail connecting said front corner posts, a horizontal bar positioned above said 5 front rail and secured to said front corner posts, a panel secured to said rail and said bar, a portion of said panel extending above said bar, a closure gate for the front of said crib, said gate including end bars connected 10 by upper and lower rails, said lower gate rail when said gate is in a closed position being positioned adjacent the top surface of said horizontal bar and adjacent the inner surface of said upwardly extending portion of said 15 panel and hinge means connecting said closure gate to said front corner portions and permitting said gate to swing outwardly through a semi-circle whereby the top of the gate in open position is disposed adjacent 20 to said front rail and whereby in closed position the bottom of the gate moves inwardly towards said rail to hold bed-clothes thereagainst.

4. In combination with a crib including 25 end portions and a back portion, each of said end portions including a vertical rear corner post and a front corner post, a horizontal rail connecting said rear corner posts and a horizontal front rail connecting said front corner posts, a horizontal bar positioned above said front rail and secured to said front corner posts, a panel secured to said front rail and said bar, a portion of said panel extending above said bar, a closure gate for the front 30 of said crib, said gate including end bars connected by upper and lower rails, and means to mount said gate for outward swinging movement whereby said lower gate rail may either be positioned adjacent the top surface 35 of said horizontal bar and in the rear of said extending portion of said panel or may be moved from such position to a position in front of said panel.

5. In combination with a crib including end 45 portions and a back portion, each of said end portions including a vertical rear corner post and a front corner post, a horizontal rail connecting said rear posts and a horizontal rail connecting said front posts, a horizontal bar positioned above said front rail and secured to said corner front posts, a panel secured to said front rail and said bar, a portion of said panel extending above said horizontal bar, a closure gate for the front of said crib, said gate including end bars, said end bars being connected by horizontal upper and lower rails, said lower gate rail when said gate is in a closed position being positioned adjacent the top surface of said horizontal bar and 50 adjacent the inner surface of said upwardly extending portion of said panel, hinge members connecting said gate to said front corner post, each of said hinge members including a central part with oppositely extending arms at the ends thereof, one of said arms 55 60 65

being pivotally connected to its associated gate end bar and the other of said arms being pivotally connected to its associated front corner post.

6. In combination with a crib including 70 end portions and a back portion, each of said end portions including a vertical rear corner post and a front corner post, a horizontal rail connecting said rear posts and a horizontal rail connecting said front posts, a horizontal bar positioned above said front rail and secured to said corner front posts, a panel secured to said front rail and said bar, a portion of said panel extending above said horizontal bar, a closure gate for the front of said 75 crib, said gate including end bars, said end bars being connected by horizontal upper and lower rails, said lower gate rail when said gate is in a closed position being positioned adjacent the top surface of said horizontal bar and adjacent the inner surface of said upwardly extending portion of said panel, hinge members connecting said gate to said front corner post, each of said hinge members being crank shaped and including a 80 shank having oppositely extending arms, one of said arms being pivotally connected to its associated gate end bar and the other of said arms being pivoted in a slot in its associated front corner post, there being a recess in each of said front corner posts communicating with said slot therein, a cover for said recess secured to said corner post, a spring in said recess, said spring engaging said second arm of said hinge member and resiliently urging it downward and releasable latch means on said gate to retain said gate in a closed position.

In testimony whereof, I hereunto affix my signature.

MAX E. ZIMMERMANN.
